COLLAPSIBLE BOX STRUCTURE

Nathan Gladstein, Bronx, N. Y.

Application February 19, 1942, Serial No. 431,561

5 Claims. (Cl. 229—41)

The present invention generally relates to collapsible box structures, and especially the kind adapted to be readily stored in parts within a minimum of space prior to being assembled.

The prime object of the present invention is to provide a plurality of relatively simple, extremely inexpensive, but effective box forming units, which are readily assemblable to produce a sturdy box structure, and which units may be easily stored and stocked in their flat position, and are provided with simple, but effective and positive locking means, which facilitate the ready mounting of a box structure at the minimum expenditure of labor and time.

Another object of this invention is to provide locking instrumentalities for said units which are so arranged that when they are forced into interengagement with one another one set of the locking elements will temporarily conform in shape to the other set of locking elements and also momentarily yield and slightly deform until the final point of interlocking is reached, whereupon the yielding elements will revert to substantially their original shape as they securely engage the other elements.

The foregoing and still further objects and important advantages of the present invention will become more fully apparent from the ensuing description and the accompanying drawing, showing presently preferred forms of my invention, which illustrations, however, are not in any way designed to restrict me to the specific structures disclosed. In the drawing:

Fig. 1 is a side elevation of a cylindrical box structure in accordance with my invention;

Fig. 2 is a top view thereof;

Fig. 3 is a plan view of a longitudinal peripheral member forming part of the box structure;

Fig. 4 is a plan view of a top or bottom member of an oval box structure;

Fig. 5 is a perspective view of a substantially cubical box structure;

Fig. 6 is a plan view of the top or bottom member of an oblong box structure;

Fig. 7 is an enlarged detail view of the interlocking elements as used in the box structure; and

Fig. 8 is a partial perspective view of another box structure with a modified arrangement of interlocking elements.

Referring now specifically to Figs. 1, 2 and 3, numeral 10 denotes the top member of a cylindrical or round box structure, while the bottom member, corresponding in shape to the top member, is indicated at 11. The side or peripheral

member 12, shown in detail in Fig. 3, comprises a longitudinal strip which forms the vertical walls of the finished box body. One or more of such side members may be used, depending upon the circumference required. For the purpose of avoiding the employment of uneconomical, long strips of material, which are unwieldy and occupy considerable space in storing, I prefer to provide relatively short pieces which I interlock with one another, as indicated at 13 in broken lines in Fig. 3.

The top and bottom members, shown in the first two figures, comprise discs provided with arcuated slots or openings 14, which are preferably evenly spaced from one another. From side member 12 extends a corresponding number of substantially narrow-shaped locking elements 15, adapted to be forced through slots 14, whereupon they interlock with the slots. The material from which the box units are made must be of a sufficient resiliency to facilitate the intended cooperation between locking elements 15 and the slots. During the locking operation, the bodies of elements 15 must temporarily conform to the shapes of the slots, and the undercut ends of the elements must be capable of momentarily yielding and to immediately spread to their erstwhile position upon reaching the other face of the slotted material. When they have thus passed through the slot, the undercut ends of the elements locking engage the ends of the slot.

In Fig. 7 I have illustrated in detail the construction of the interlocking elements. There is shown an arcuated slot 14 in one part of the structure 10 and a substantially arrow-shaped locking element 15 extending from member 12. Broken lines 16 indicates the alternative shape of a locking element, such as employed in Figs. 1, 2 and 3. It will be observed that locking element 15 forms an integral part of member 12 and comprises a solid body portion 17, terminating in substantially reduced tips 18, which are separated from the body of member 12 by undercuts 19. These undercuts provide a reduced connection or neck 20 between body 17 of the element and the body of member 12. It will be observed that the width dimension of neck 20 is somewhat less than the length of slot 14, as indicated by broken extension lines 21. When now locking element 15 is forcibly passed through slot 14, the body 17 of the locking element will curve in conformity with the arc of slot 14, and ends or tips 18 of element 15 will be momentarily pressed inwards until they have passed through the slot. At that moment they resume substantially their

original position, and positively interlock with the ends of slot 14. At the same time body 17 will also revert to substantially its original flat shape, although it may remain slightly curved, as indicated in Fig. 1, which however is not objectionable.

In Figs. 1 to 3 I provide slots in the top and bottom members, while from the side member or members extend locking elements 15. A reverse arrangement is shown in Fig. 8 where locking elements 15' are stamped out from within the bodies of top member 22 and bottom member 23, whereas arcuated slots 14' are cut along the top and bottom marginal edges of peripheral member 24. In this arrangement the arrow-shaped locking elements are bent towards each other before they are passed through their respective slots in the circumferential member.

While in Figs. 1 and 8 round box structures are indicated, it is quite obvious that the shape of the box structure may be altered. In Fig. 4 an oval top or bottom member 25 is shown, provided with a correspondingly higher number of arcuated slots 26. Similarly in Fig. 6 an oblong top or bottom member 27 is illustrated, in which are provided arcuated slots 28. In Fig. 5 a small container is shown with substantially square-shaped top and bottom members 29 and 30, both provided with four slots for the reception of a corresponding number of interlocking elements 31 extending from side member 31. It will be observed that the interlocking elements shown in Figs. 1 to 5 remain extending upwardly, although they may be folded down if desired.

In all of the constructions illustrated and described, the interlocking of the elements takes place in the same manner as explained in connection with Fig. 7. It is immaterial whether the shape of the locking element 15 is of a pointed form, shown in Figs. 2 or 5, or is of a rounded shape, seen in Fig. 1, as long as it substantially conforms to an arrow-shaped structure wherein the body of the locking element is connected with the body of the member from which it extends by a distinct neck portion and wherein the tips or ends of the element possess straight engaging edges produced by a straight undercut. Such undercut, in the structure shown in Figs. 1 and 5, corresponds approximately to the thickness of the box material. In the construction illustrated in Fig. 8 the neck portion is somewhat longer.

The interlocking arrangement for the peripheral member or members 12 is identical with that employed for connecting the top and bottom members, as clearly indicated in Fig. 2, wherein an arcuated slot 32 is shown at one end of the longitudinal member and a corresponding substantially arrow-shaped interlocking element 33 at the other end. The number of end interlocking elements may of course be multiplied when a wide peripheral member is employed for a high box structure.

While I have illustrated and described specific constructions of my collapsible box arrangement, be it understood that changes and improvements may be readily incorporated therein within the broad scope of my invention, as defined in the annexed claims.

I claim:

1. In a collapsible box structure, top and bot-

tom members and at least one longitudinal peripheral member in engagement with the former members, locking means arranged with all members and comprising uniformly spaced, arcuated peripheral slots in the top and bottom members and correspondingly spaced, substantially arrow-shaped locking elements provided at the top and bottom edges of the peripheral member, said locking elements forming integral parts of said latter member and being sufficiently resilient and so constructed that, when forced through their corresponding slots, they temporarily conform to the arcuated shape of the latter and yield, but spread immediately to substantially their original

shape upon having passed through the slots and locking engage both ends of the slots.

2. In a collapsible box structure, as set forth in claim 1, said locking elements comprising solid body portions terminating in substantially reduced ends at their broadest dimension, undercuts separating these ends from the body of the member from which they are formed, said undercuts forming necks of a width slightly less than the length of said slots.

3. In a collapsible box structure, a flat top member, a similarly shaped bottom member, a plurality of spaced, arcuated slots arranged marginally along the peripheries of both members, a peripheral member disposed between and connecting the top and bottom members, a plurality of substantially arrow-shaped, undercut locking elements extending from both edges of and constituting integral parts of said peripheral member and in locking engagement with the slots of the top and bottom members, the dimensions of the undercuts of the locking elements corresponding to the thickness of material of said top and bottom members, the undercuts forming necks connecting the bodies of the elements with the body of the peripheral member, and the width of the necks being somewhat less than the length of the slots, said undercuts rendering the ends of the elements yieldable so that they may be temporarily deformed while the elements are forcibly passed through the slots, whereupon they resume their original position and engage both ends of the slots.

4. In a collapsible box structure, as set forth in claim 3, said peripheral member comprising a longitudinal flat body provided at one end with at least one arcuated slot and at least one substantially arrow-shaped locking element at its other end, adapted to interlock with said slot.

5. In a collapsible box structure, top and bottom members and a peripheral member connecting them, all three members being provided with substantially peripheral, evenly spaced, interlockable instrumentalities, comprising a combination of marginal, arcuated slots and substantially flat, arrow-shaped locking elements of a sufficient resiliency to allow forcing them through the slots and bowing them temporarily to the shapes of the slots, said elements being adapted to assume their flat shapes after having passed through the slots, and to engage with both of their undercut end tips both end edges of the slots.
